UNITED STATES PATENT OFFICE.

LINN BRADLEY, OF MONTCLAIR, NEW JERSEY, AND EDWARD P. MCKEEFE, OF PLATTSBURGH, NEW YORK, ASSIGNEES TO BRADLEY-MCKEEFE CORPORATION, OF NEW YORK, N. Y., A CORPORATION OF NEW YORK.

PRODUCTION OF COMPOSITE COOKING LIQUOR.

No Drawing. Original application filed February 8, 1922, Serial No. 535,034. Divided and this application filed March 2, 1925. Serial No. 12,762.

This invention relates to improvements in the production of composite cooking liquors containing caustic soda and a three element sodium compound containing sulfur, such as 5 sodium sulfite, either with or without other sodium compounds. More particularly, the invention relates to an improved process of treating the residual liquors resulting from the cooking of wood with a composite liquor 10 containing caustic soda and sodium sulfite for the regeneration of cooking liquors therefrom for use in the further carrying out of the cooking process.

In our prior parent application, Serial No. 15 535,034, filed February 8, 1922, we have described a process for the production of wood pulp from wood which is carried out with a cooking liquor consisting essentially of caustic soda together with normal sodium sulfite, 20 with the caustic soda present in preponderating amount, that is, with the amount of sodium present as sulfite not exceeding the amount of sodium present as caustic soda, and ordinarily with the amount of sodium sulfite smaller in sodium content than that of 25

the caustic soda, for example, from ten to twenty-five percent of the total sodium present being present as sodium sulfite. In such cooking processes, the caustic soda, although 30 in preponderating amount, is nevertheless so controlled in amount and concentration in the cooking liquor that it does not exert any excessively destructive action on the fibers of the wood.

35 The residual liquors produced as a result of such cooking process are themselves of distinctive composition and can be readily treated, according to the present invention, for the regeneration of the cooking liquors. We 40 have found that these residual liquors can be advantageously treated by the ordinary procedure and apparatus employed in the treatment of black liquors from the soda process, provided the operations are specially regulated, and even though the residual liquors 45 and cooking liquors of the present invention contain a considerable amount of sodium sulfite.

The composition of the cooking liquor used 50 in the cooking process, and which is to be regenerated by the process of the present invention, may vary somewhat in its composition.

The cooking liquor may, for example, for 55 poplar wood, have a strength of about 15° or 16° Twaddell and may be e. g. of 90% causticity based on Na_2CO_3 . In general, the liquors may contain from 50 to 60 grams per liter of caustic soda and from 10 to 25 grams per liter of normal sodium sulfite, although an even larger amount of sulfite, up to an 60 amount equal to that of the caustic soda may be used, preferably with corresponding reduction in the amount and proportion of the caustic soda. With dense hard woods a radically increased amount of the reagents 65 should be used, but in that case the sodium sulfite should be increased, without a corresponding increase in caustic soda, so that the amount and strength of caustic soda in the composite cooking liquor will be kept below 70 the amount which will cause any considerable injury to the fibers of the pulp produced. For example, with dense hard woods, the cooking liquor may be made up of caustic soda and sodium sulfite in approximately 75 equal amounts, so far as their sodium content is concerned.

It is one advantage of the cooking process using such a composite cooking liquor that a 80 materially increased yield of pulp is obtained from the wood, and a correspondingly decreased amount of the wood substance is dissolved away into the residual liquors, as compared, for example, with the soda process. The residual liquors, moreover, are distinguished 85 in their properties and composition from the ordinary black liquor of the soda process, and also from the so-called black liquor of the sulfate process. The residual liquors are also distinguished from the so-called waste sulfite liquors of the acid sulfate process. The residual liquor, like the cooking liquor, is of a composite character. The cooking process combines the 90 reactions of the caustic soda and of the sulfite 95 present, although the liquor is not acid, as is the liquor of the acid sulfite process, nor is it as strongly alkaline as the liquor of the ordinary soda process.

If the residual liquors, made with the composite caustic and sulfite cooking liquor, were 100 concentrated and calcined under strongly oxidizing conditions, the greater part or all of the sulfite or sulfite-reaction products would

be decomposed with setting free of sulfur dioxide and the formation of sodium carbonate as the primary if not the sole sodium compound of the calcined product. On the other hand, if the residual liquor is concentrated and subjected to calcination under smelting conditions, reduction of the sulfite or sulfate reaction products will take place to a greater or lesser extent, with the resulting production of sodium sulfide in the calcined product. The former process is included in our former co-pending application Serial No. 513,161, filed November 5, 1928, the latter in our co-pending application Serial No. 686,137, filed 15 January 14, 1924.

According to the present invention, the residual liquor is concentrated and then calcined under regulated conditions, whereby a considerable amount of sodium sulfite is directly recovered, together with sodium carbonate, and with or without small and varying amounts of other sodium salts, from the calcined product.

We have found that the residual liquors can be readily treated for the regeneration of the cooking liquors by subjecting them to evaporation in multiple effect evaporators and by calcining the resulting concentrated liquor in rotary calcining furnaces, such as used in the calcining of black liquor from the ordinary soda process. Owing to the decreased amount of wood substance contained in solution in the residual liquors (e. g. from poplar wood), the liquors are less gummy in character and give less trouble in the evaporators from foaming or gumming, etc. The liquor, from the strong liquor tank, of a strength of around 14 to 14.5° Twaddell at a temperature of 155 to 160° F. can be readily concentrated in quadruple effect evaporators to 60 or 65° Twaddell, or even higher, at a temperature of 140 to 144° F. The concentrated liquor can then be fed to the rotary calcining furnaces such as are used in treating black liquors from the ordinary soda process.

We have found that, although the residual liquors contain a considerable amount of combined sulfur they can nevertheless be calcined in the rotary furnaces without driving off the entire amount of the combined sulfur. We have also found that sodium sulfite comes from the rotary calcining furnaces without any considerable amount of reduction by the admixed organic matter, a few per cent, only of sulfide being formed. The rotary calcining furnaces may, for example, have a diameter of about 9 feet and a length of about 16 feet and may be heated by coal fire. The concentrated residual liquor from the multiple effect evaporators, concentrated to about 60-65° Twaddell can be fed into the rotary furnaces at one end and the calcined product discharged at the other. With proper control of the calcination, such that fusion

of the discharged product is avoided as much as possible, the sulfite comes from the furnace in considerable amount.

The calcined product can then be leached, for example, by introducing it into water and agitating the water, or by otherwise carrying out the leaching operation. By counter-current leaching a solution can be obtained up to 27-31° Twaddell. This liquor can be subjected to causticizing with lime to convert its contained sodium carbonate for the most part into caustic soda, using, for example, 53 or 54 parts of calcium oxide to 100 parts of sodium carbonate. The sulfite contained in the liquor is advantageously not causticized, and the amount of lime should be kept sufficiently low to avoid this. The causticizing operation can be carried out by heating and agitating for a sufficient period of time to carry the causticizing to the desired degree. Some sodium carbonate will usually be left uncausticized in the resulting liquor, which will be made up for the most part of caustic soda, resulting from the causticizing operation, and sodium sulfite. Some small and incidental amount of sodium sulfide may also be present, produced during the calcination, but we have found that, by avoiding smelting of the charge during calcination, there is no building up of sulfide to an objectionable degree nor is there any excessive building up of sulfate, but the sulfite in considerable part passes through the furnace and is recovered for further use, while such small and incidental amounts of sodium sulfide as may be formed and as may be present in the regenerated liquor, are without any objectionable effect in the process when carried out with the regenerated cooking liquor, although such amounts of sodium sulfide can be readily removed, if desired.

In order to make up for losses of caustic soda and sodium sulfite, a suitable amount of dry soda ash, for example, may be added to the liquor before causticizing, while the necessary amount of sodium sulfite can be readily produced, for example, by burning sulfur in a small sulfur burner and absorbing the sulfur dioxide in a solution of soda ash or a solution which contains the sodium carbonate leached from the calcined product above described.

The process of the present invention enables the pulp manufacture to be made regenerative or cyclic in character, with the use of a cooking liquor of a composite character, containing essentially caustic soda and sodium sulfite, and with treatment of the residual liquors for the regeneration therefrom of the cooking liquor containing essentially the same ingredients, with or without the admixture of small and varying amounts of other ingredients. This cyclic or regenerative process involves the cooking of the wood chips with the composite cooking liquor,

evaporation of the residual liquor and calcination of the concentrated liquor, with regulation of the calcining operation, and with avoiding of smelting, so that the sodium sulfite and other required chemicals are recovered without excessive loss, and with leaching of the calcined material and causticizing of the leached liquor with lime, using a regulated amount of lime such that the major portion of the sodium carbonate is causticized without, however, causticizing the sodium sulfite, thus recovering essentially a mixture of caustic soda and sodium sulfite in a form available for use in the further carrying out of the process, with such additions as may be required to make up the composition of the liquor to that desired in the cooking operation.

The residual liquor treated in the process of the present invention, is, as above stated, of a distinctive and characteristic composition. It contains less dissolved fibrous material and consequently less organic matter. It can be readily evaporated without difficulty; and it acts in a characteristic way when subjected to calcination, and when the calcining operation is regulated in the manner above described. From the calcined material the new cooking liquor can be produced by a regulated causticizing operation, regulated and controlled in the manner above indicated, with addition of fresh amounts of chemicals to make up for losses of soda or of the sulfite radical during the regenerative process.

The residual liquors treated in the present process, because of their different composition, and particularly because of their content of three element sodium salts containing sulfur, are readily fused unless proper control of the calcination is effected. With such proper control, fusion can be avoided to such an extent that the sulfite comes from the furnace and is present in the calcined product in considerable amount. Moreover, by avoiding smelting of the charge during calcination, and regulating the calcination to avoid smelting, there is no building up of sulfide to an objectionable degree, but the sulfite in considerable part passes through the furnace and is recovered for further use. Such small and incidental amounts of sodium sulfide as may be formed and as may be present in the liquor leached from the calcined product may be left in the liquor or may be removed. When the leached liquor is used for absorbing sulfur dioxide, some or all of the sulfide will be converted into thiosulfate and the latter will then be present in the regenerated liquor.

The recovery of some of the desired three element sodium compounds containing sulfur, such as sodium sulfite, from the calcined product, reduces to a corresponding extent the amount of such compounds which it is

necessary to add or form by further treatment from the leached liquor. Moreover, when the leached liquor, with its large content of sodium carbonate, is causticized, the causticizing operation is regulated to convert the desired amount of sodium carbonate into caustic soda, but without causticizing the desired three element sodium-sulfur compounds, such as sodium sulfite. The present invention, accordingly, includes a partial or fractional causticizing of the leached liquor with an amount of lime insufficient to causticize the sodium sulfite, etc. content of the liquor, but sufficient to causticize the sodium carbonate content to the desired degree.

We do not claim herein the complete cyclic process for the manufacture of pulp and paper which includes the treatment of residual liquor in accordance with the present application, inasmuch as this complete cyclic process is claimed in our parent application Serial No. 535,034.

We claim:

1. The method of regenerating a cooking liquor containing caustic soda and sodium sulfite from a residual liquor resulting from the cooking of wood with such a cooking liquor, which comprises concentrating the residual liquor, calcining the same in a rotary furnace under conditions to give a calcined product containing sodium sulfite and sodium carbonate, leaching the calcined material and causticizing the resulting solution with an amount of lime insufficient to causticize the sodium sulfite therein.

2. The method of treating residual liquor, resulting from the cooking of wood with a cooking liquor containing a preponderating amount of caustic soda and a lesser amount of sodium sulfite which comprises subjecting the liquor to concentration and calcination, regulating the calcination to avoid any considerable fusion of the calcined product, leaching the calcined product and incompletely causticizing the resulting solution.

3. The method of treating residual liquor resulting from the cooking of wood with a cooking liquor containing sodium sulfite which comprises subjecting the liquor to concentration and calcination and regulating the calcining operation to avoid smelting of the calcined product.

4. The method of treating residual liquor resulting from the cooking of wood with a cooking liquor containing sodium sulfite which comprises subjecting the liquor to concentration and calcination and regulating the calcining operation to give a calcined product containing a considerable amount of sodium sulfite.

5. The method of treating residual liquor, resulting from the cooking of wood with a cooking liquor containing a preponderating amount of caustic soda and a lesser amount of sodium sulfite which comprises subjecting the

liquor to concentration and calcination, and regulating the calcination to avoid any considerable fusion of the calcined product.

6. The method of treating residual liquor, resulting from the cooking of wood with a cooking liquor containing sodium sulfite, which comprises subjecting the liquor to concentration and calcination, and regulating the calcination to avoid any considerable fusion of the calcined product.

7. The method of treating residual liquor, resulting from the cooking of wood with a cooking liquor containing caustic soda and also containing a three element compound of sodium which contains sulfur, which comprises subjecting the liquor to concentration and calcination, and regulating the calcination to avoid any considerable fusion of the calcined product.

20 8. The method of treating residual liquor, resulting from the cooking of wood with a cooking liquor containing caustic soda and also containing a three element compound of sodium which contains sulfur, which comprises subjecting the liquor to concentration and calcination, regulating the calcination to avoid smelting, leaching the calcined product and incompletely causticizing the resulting solution.

30 9. The method of treating residual liquor, resulting from the cooking of wood with a cooking liquor containing caustic soda and also containing a three element compound of sodium which contains sulfur, which comprises concentrating the liquor, supplying the concentrated liquor to a calcining furnace with completion of the evaporation and production of a calcined product, and regulating the calcining operation to avoid smelting of the calcined product.

40 10. The method of treating residual liquor, resulting from the cooking of wood with a cooking liquor containing caustic soda and also containing a three element compound of sodium which contains sulfur, which comprises concentrating the liquor in multiple effect evaporators, supplying the concentrated liquor to a rotary calcining furnace with resulting completion of evaporation and production of a calcined product and regulating the calcining operation to avoid any considerable fusion of the calcined product.

50 11. A process of recovering sodium sulfur salts from residual liquor, resulting from the cooking of wood with a cooking liquor containing caustic soda and three element sodium sulfur salts, which includes the step of supplying the liquor to a calcining furnace and evaporating the liquor to dryness and calcining the dried product therein, the calcining being regulated to avoid smelting of the calcined product.

60 12. The method of treating residual liquor, resulting from the cooking of wood with a

cooking liquor containing caustic soda and 65 also containing a three element compound of sodium which contains sulfur, which comprises concentrating the liquor in multiple effect evaporators, supplying the concentrated liquor to a rotary calcining furnace 70 with resulting completion of evaporation and production of a calcined product, regulating the calcining operation to avoid any considerable fusion of the calcined product, leaching the calcined product and incompletely 75 causticizing the leached liquor.

13. A process of recovering sodium sulfur salts from residual liquor, resulting from the cooking of wood with a cooking liquor containing caustic soda and three element sodium sulfur salts, which includes the step 80 of supplying the liquor to a calcining furnace and evaporating the liquor to dryness and calcining the dried product therein, the calcining being regulated to avoid smelting 85 of the calcined product, leaching the calcined product and incompletely causticizing the leached liquor.

14. The method of treating residual liquor, resulting from the cooking of wood with a 90 cooking liquor containing caustic soda and also containing a three element compound of sodium which contains sulfur, which comprises concentrating the liquor, supplying the concentrated liquor to a calcining 95 furnace with completion of the evaporation and production of a calcined product, regulating the calcining operation to give a calcined product containing a considerable amount of the three element sodium sulfur 100 compound used in the cooking liquor, leaching the calcined product and incompletely causticizing the same.

15. The method of treating residual liquor resulting from the cooking of wood with a 105 cooking liquor containing a preponderating amount of caustic soda and a lesser amount of a three element sodium sulfur compound containing oxygen which comprises concentrating the residual liquor, supplying the 110 concentrated liquor to a rotary calcining furnace and evaporating the same to dryness and calcining the dried product therein, regulating the calcining operation to leave in the calcined product a substantial amount of the 115 three element sodium sulfur compound containing oxygen suitable for use in the production of further amounts of cooking liquor, leaching the calcined product and incompletely causticizing the resulting solution to 120 give a partially causticized liquor containing a preponderating amount of caustic soda.

16. The method of treating residual liquor, resulting from cooking of wood with a cooking liquor containing caustic soda in a preponderating amount and also containing a three element sodium sulfur compound which comprises subjecting the liquor to concentra- 125

tion and calcination and regulating the calcining operation to avoid smelting of the calcined product.

17. The method of treating residual liquor 5 resulting from the cooking of wood with a cooking liquor containing a preponderating amount of caustic soda and a lesser amount of a three element sodium sulfur compound, which comprises subjecting the liquor to concentration and calcination, regulating the calcining operation to give a calcined product containing a considerable amount of the three element sodium sulfur compound, leaching the calcined product and incompletely causticizing the same to give a solution containing a preponderating amount of caustic soda.

18. The method of treating residual liquor, resulting from the cooking of wood with a cooking liquor containing a preponderating 20 amount of caustic soda and also containing sodium sulfite which comprises concentrating the liquor in multiple evaporators, feeding the concentrated liquor to a rotary calcining furnace and evaporating the same to dryness 25 and calcining the dried product therein, regulating the calcination to give a calcined product containing a considerable amount of sodium sulfite, together with sodium carbonate and varying amounts of other sodium salts, 30 leaching the calcined products and incompletely causticizing the same to give a solution containing a preponderating amount of caustic soda.

19. The method of regenerating a cooking 35 liquor containing caustic soda and sodium sulfite from a residual liquor resulting from the cooking of wood with such a cooking liquor, which comprises concentrating the residual liquor, calcining the same in a rotary 40 furnace with regulation of the calcination to

avoid smelting, leaching the calcined material, incompletely causticizing a portion of the leached solution, sulfiting another portion of the leached solution and mixing the causticized and sulfited portions.

45

20. The method of treating residual liquor resulting from the cooking of wood with a cooking liquor containing sodium sulfite which comprises calcining the residual liquor under conditions to substantially avoid oxidation or reduction of the sodium sulfite.

50

21. The method of treating residual liquor resulting from the cooking of wood with a cooking liquor containing sodium sulfite which comprises calcining the residual liquor under conditions regulated to produce a calcined product containing substantially only sodium sulfite and sodium carbonate.

55

22. The method of treating residual liquor resulting from the cooking of wood with a cooking liquor containing sodium sulfite which comprises calcining the residual liquor under conditions regulated to substantially avoid the production of sodium sulfide and sodium sulfate.

60

23. The method of treating residual liquor resulting from the cooking of wood with a cooking liquor containing sodium sulfite which comprises calcining the residual liquor, leaching the calcined product and treating the leached liquor for the production of cooking liquor containing sodium sulfite, the calcining and subsequent treatments being regulated to substantially prevent the formation of sodium thiosulfate in the cooking liquor.
